MOTORCYCLE LAMP

Sherman E. Taylor, 3307 N. MacArthur,
Oklahoma City, Okla. 73122

Filed Jan. 31, 1972, Ser. No. 222,436

Term of patent 14 years

Int. Cl. D26—06

U.S. Cl. D48—32 R

FIG. 1 is a perspective view of a motorcycle lamp showing my new design, the motorcycle being shown in broken lines for illustrative purposes only;

FIG. 2 is an enlarged perspective view thereof;

FIG. 3 is an enlarged bottom plan view thereof;

FIG. 4 is an enlarged front elevational view thereof as seen from the top of FIG. 3;

FIG. 5 is an enlarged side elevational view thereof as seen from the right of FIG. 3;

FIG. 6 is a greatly enlarged cross-sectional view taken on line 6—6 of FIG. 2; and

FIG. 7 is a greatly enlarged cross-sectional view taken on line 7—7 of FIG. 2.

I claim:

The ornamental design for a motorcycle lamp, as shown and described.
